PISTON CONSTRUCTION

William Wuerfel, Philadelphia, Pa., assignor to
Wilkening Manufacturing Company, Philadelphia, Pa., a corporation of Delaware

Application June 30, 1933, Serial No. 678,493

15 Claims. (Cl. 309—12)

The present invention relates to a new and useful piston and piston construction, the lower or skirt portion of which is split longitudinally and is resiliently expanded, so as to cause the skirt to expand radially, and also relates to a new and useful method or process of making pistons so as to impart resiliency to the skirt portions thereof.

The object of the present invention is to provide a split-skirt type piston, wherein the skirt is caused to expand outwardly against the cylinder wall by a generally uniform and predetermined force, so as to prevent the skirt from collapsing or fluttering at high piston speed, and so as to maintain the skirt in a generally round or circular formation.

With the above and other objects in view, which will appear more fully from the following detailed description, the present invention consists in longitudinally slotting or splitting the skirt or lower portion of the piston, from its lowermost edge up to some point beneath the bottom ring-receiving groove, then slotting the skirt also transversely to a suitable extent at the upper end or head end of the longitudinal slot or split, so as to permit a certain amount of expansion and contraction in the split portion of the skirt, providing suitable grooves in the juxtaposed split edges of the skirt, and so positioning a generally corrugated spring member in said groove, as to cause the same to exert a generally tangential force upon the two longitudinal split edges of said skirt, in opposite directions, so as to tend to expand said skirt.

The present invention further consists of other novel details of construction, all as will more fully appear from the following detailed description.

For the purpose of illustrating the invention, there is shown in the accompanying drawings one form thereof which is at present preferred, since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

Referring to the drawings in which like reference characters indicate like parts:

Figure 1 represents a front elevational view of a piston embodying the present invention.

Figure 2 represents a bottom plan view of the same.

Figure 3 represents a plan view of the corrugated spring member.

Figure 4 represents a perspective view of the

cutting tool which may be employed in forming the grooves in the longitudinal split edges of the skirt.

Figure 5 represents a section which may be referred generally to line 5—5 of Figure 1, on a much enlarged scale, illustrating a modified embodiment of the present invention, wherein a flat, waved or corrugated ribbon type spring is employed with the corrugations or undulations being in a generally radial direction instead of tangentially, as in the modification shown in Figures 1, 2, and 3.

Figure 6 represents a section generally on line 6—6 of Figure 5.

Figure 7 is a section similar to that shown in Figure 5, illustrating a further modification of the present invention.

The piston 5, of the present invention, may be of any suitable type, and formed of any suitable metal, having any suitable number of ring-receiving grooves 6 and having a lower skirt portion 7, and wrist pin bearings 8 and 9 formed integrally with the piston.

Intermediate the pair of wrist pin bearings 8 and 9, a relatively narrow parallel portion of the piston skirt 7 is removed by any suitable cutter, or the piston may be formed initially with the slight gap or space 10 in the skirt 7. This leaves the skirt split along one generally longitudinal line. A transverse slot 11 is also provided in the skirt, at the upper end of the gap or slot 10, so as to give the two halves of the skirt, on either side of the slot 10, greater freedom of expansion and contraction.

In the juxtaposed edges 12 and 13 of the skirt 7, corresponding grooves 14 and 15 are provided, by means of the tool 16 shown in Figure 4. The tool 16 includes a shank portion, which may be suitably gripped in any milling machine, and a cutter portion 17, having opposite cutting edges 18. The tool 16 rotated in the head of the milling machine is then fed through the slot 10 while rotating at a suitable speed, and generally parallel to the slot, so as to form opposed grooves 14 and 15 in the free edges of said slot.

The expander spring 19 is formed of suitable spring wire, of suitable thickness, and is formed with generally similar corrugations 20.

The upper end 21 of the spring 19 is extended slightly beyond the general outline of the spring, so as to cause said end 21 to project into the slot 11 to a suitable extent, thereby to lock the spring 19 in the grooves 14 and 15 and to prevent it from sliding out. Thus the spring 19 is inserted merely by slipping it in at the lower end,

and it is forced into the grooves 14 and 15 until the slightly enlarged end 21 of the spring snaps into the transverse slot 11. When thus snapped in place, the spring is effectively locked against 5 any longitudinal displacement. Hence the reciprocation of the piston has no effect upon the security of the spring in the piston.

The transverse overall dimension of the spring 19 in its normal or unstressed condition is greater 10 than the normal distance between the bottom of the groove 14 and the bottom of the groove 15, by an extent sufficient to tension the spring 19 when inserted into said groove, to the desired extent. When the spring 19 is inserted into 15 grooves 14 and 15, the spring is tensioned transversely, and exerts a tangential force generally equal to this tension.

This tangential force exerted generally uniformly throughout the length of the slotted portion 20 of the skirt, causes the skirt to be expanded against the cylinder wall so as to prevent the collapsing of the piston skirt and to prevent the flutter of the piston skirt at high speeds. This also tends to expand the skirt under all operating 25 conditions.

In Figures 5 and 6, a modified form of the present construction is illustrated, wherein a flat ribbon type spring member 25, of generally waved, corrugated or crimped form is employed 30 in the grooves 14 and 15 cut into the piston skirt 7. The corrugations, as seen in Figures 5 and 6, extend generally in a radial direction, so that the direct force resulting from the compression of the spring or the partial flattening out of 35 the corrugations thereof, is exerted in a generally radial direction indicated by the arrows 26, while the resultant force is exerted in a generally tangential direction indicated by the arrows 27. This resultant tangential force is caused by the 40 inclination of the contacting surface of the groove. While in Figures 5 and 6, the groove is shown of curved cross-section, the desired inclination may be produced by the formation of V-shaped grooves instead of grooves of curved 45 or circular cross-section, as indicated in Figure 7;—it being necessary for the second embodiment of my invention merely to have inclined side walls to coat with the generally radially expanding spring element.

50 The invention may be embodied in other specific forms without departing from the spirit or essential attributes thereof, and it is desired therefore that the present embodiment be considered in all respects as illustrative and not 55 restrictive, reference being had to the appended claims rather than to the foregoing description to indicate the scope of the invention.

I claim:

1. The combination of a trunk type piston 60 having the skirt portion thereof slotted generally longitudinally and having also a generally transverse slot in communication with said generally longitudinal slot near the inner end of the latter (that is, nearest the head-end of the piston) so as to permit expansion and contraction of said skirt, recesses formed in the juxtaposed sides of said longitudinal slot, and a generally corrugated spring member operatively interposed between the two juxtaposed sides of said generally longitudinal slot, said spring including means extending into and coacting with said recesses for retaining said spring member against generally radial displacement in relation to the piston skirt, 65 and including means cooperating with the walls of said transverse slot to retain said spring member against generally longitudinal displacement in relation to the piston skirt.

member against generally longitudinal displacement in relation to the piston skirt.

2. The combination of a trunk type piston having the skirt portion thereof slotted generally longitudinally and having also a generally transverse slot in communication with said generally longitudinal slot near the inner end of the latter (that is, nearest the head-end of the piston) so as to permit expansion and contraction of said skirt, and having the skirt-wall portions immediately marginal to said slot of generally the same over-all radial thickness as the principal radial thickness of the major portion of the skirt-wall, recesses formed in the juxtaposed sides of said longitudinal slot, and a generally corrugated 15 spring member operatively interposed between the two juxtaposed sides of said generally longitudinal slot, said spring including means extending into and coacting with said recesses for retaining said spring member against generally 20 radial displacement in relation to the piston skirt, and including means cooperating with the walls of said transverse slot to retain said spring member against generally longitudinal displacement in relation to the piston skirt. 25

3. The combination of a trunk type piston having the skirt portion thereof slotted generally longitudinally and having also a generally transverse slot in communication with said generally longitudinal slot near the inner end of the latter 30 (that is, nearest the head-end of the piston) so as to permit expansion and contraction of said skirt, recesses formed in the juxtaposed sides of said longitudinal slot, and a generally corrugated spring member operatively interposed between 35 the two juxtaposed sides of said generally longitudinal slot, with its convolutions extending generally tangentially, said spring including means extending into and coacting with said recesses for retaining said spring member against generally 40 radial displacement in relation to the piston skirt, and including means cooperating with the walls of said transverse slot to retain said spring member against generally longitudinal displacement in relation to the piston skirt. 45

4. The combination of a trunk type piston having the skirt portion thereof slotted generally longitudinally and having also a generally transverse slot in communication with said generally longitudinal slot near the inner end of the latter 50 (that is, nearest the head-end of the piston) so as to permit expansion and contraction of said skirt, and having the skirt-wall portions immediately marginal to said slot of generally the same over-all radial thickness as the principal radial 55 thickness of the major portion of the skirt-wall, recesses formed in the juxtaposed sides of said longitudinal slot, and a generally corrugated spring member operatively interposed between the two juxtaposed sides of said generally longitudinal slot, with its convolutions extending generally tangentially, said spring including means extending into and coacting with said recesses for retaining said spring member against generally 60 radial displacement in relation to the piston skirt, and including means cooperating with the walls of said transverse slot to retain said spring member against generally longitudinal displacement in relation to the piston skirt. 65

5. A piston having a skirt slotted generally 70 longitudinally and having opposed parallel grooves in the juxtaposed faces of said longitudinal slot intermediate the inner and outer generally cylindrical surfaces of said piston skirt, and of a transverse width substantially less than 75

the principal radial thickness of the major portion of the skirt the longitudinal slot in said skirt extending radially through the skirt wall so as to permit free radial movement of the skirt portion on each side of the slot with respect to the skirt portion on the other side of the slot, and a corrugated spring member operatively interposed between the two juxtaposed sides of said longitudinal slot and in operative engagement with said grooves, tending to exert opposed tangential forces upon said skirt to expand the same.

6. A piston having a skirt slotted generally longitudinally and have opposed parallel grooves in the juxtaposed faces of said longitudinal slot, intermediate the inner and outer generally cylindrical surfaces of said piston skirt, and of a transverse width substantially less than the principal radial thickness of the major portion of the skirt, the longitudinal slot in said skirt extending radially through the skirt wall so as to permit free radial movement of the skirt portion on each side of the slot with respect to the skirt portion on the other side of the slot, and a corrugated spring member operatively interposed between the two juxtaposed sides of said longitudinal slot, and in operative engagement with said grooves tending to exert opposed tangential forces upon said skirt to expand the same, and with the median portions of said corrugated spring being radially unbound-
30 ed and clear of the piston skirt wall, and said slotted edges of the piston skirt being in generally pivotal relation to said spring member.

7. A piston having the skirt portion thereof slotted generally longitudinally so as entirely to disconnect the two parts of the skirt on either side of the slot in the zone of the slot and so as to permit the independent radial expansion and contraction of the skirt portions on either side of the slot, recesses formed in the juxtaposed sides 40 of said longitudinal slot, a generally corrugated spring member operatively interposed between the two juxtaposed sides of said generally longitudinal slot, said spring including means extending into and coacting with said recesses for retaining said spring member against generally radial displacement in relation to the piston skirt, and including means in interlocking engagement with said piston to retain said spring member against generally longitudinal displacement in relation to 45 the piston skirt.

8. The combination of a trunk type piston having a skirt slotted generally longitudinally and having the skirt wall portions immediately marginal to said slot of generally the same over-all 50 radial thickness as the principal radial thickness of the major portion of the skirt wall, a groove provided in each of the opposite side-walls of the slot in said skirt, and a spring member operatively interposed between the slot edges of said skirt within said groove; said skirt having a transverse slot at the inner end of said longitudinal slot (that is, nearest the head-end of the piston) and the inner end of said spring projecting into 55 said transverse slot.

9. The combination of a trunk type piston having a skirt slotted generally longitudinally at a slight angle with respect to the axis of the piston, said piston skirt also having a transverse slot at the inner end of said generally longitudinal slot (that is, nearest the head-end of the piston) and communicating therewith, a groove formed in each of the opposite side-walls of the slot in said skirt, and a generally corrugated spring member 60 interposed between the two sides of the skirt on

either side of the slot, said spring member being disposed within said groove, and having its inner end projecting into said transverse slot, thereby to lock the spring against longitudinal displacement while the piston is in operation.

10. The combination of a trunk type piston having a skirt slotted generally longitudinally and having the skirt wall portions immediately marginal to said slot of generally the same over-all radial thickness as the principal radial thickness of the major portion of the skirt wall, a groove provided in each of the opposite side walls of the slot in said skirt, and a spring member operatively interposed between the slot edges of said skirt within said groove, said skirt having a transverse slot at the inner end of said longitudinal slot (that is, nearest the head end of the piston) and the inner end of said spring member projecting beyond the general outline of such member and into said transverse slot 20 for a substantial distance.

11. The combination of a piston having a skirt slotted generally longitudinally and having the skirt wall portions immediately marginal to said slot of generally the same over-all radial thickness as the principal radial thickness of the major portion of the skirt wall, a groove provided in each of the opposite side walls of the slot in said skirt, and a spring member structurally distinct from said piston and having oppositely curved coplanar bends operatively interposed between the slot edges of said skirt within said grooves and bearing alternately on the surface of the grooves to interlock with said grooves so as to prevent displacement thereof with respect to the piston skirt in a radial direction, without restraining the independent radial expansion and contraction of the skirt portions on opposite sides of the slot.

12. The combination of a piston having a skirt slotted generally longitudinally and having opposed parallel grooves in the juxtaposed faces of said longitudinal slot intermediate the inner and outer generally cylindrical surfaces of said piston skirt, and of a transverse width substantially less than the principal radial thickness of the major portion of the skirt;—the longitudinal slot in said skirt extending radially through the skirt wall so as to permit free radial movement of the skirt portion on each side of the slot with respect to the skirt portion on the other side of the slot, and a spring member operatively interposed between the two juxtaposed sides of said longitudinal slot and in operative engagement with said grooves and in generally pivotal relation to the juxtaposed sides of said slot, tending to exert opposed tangential forces upon said skirt to expand the same.

13. The combination of a piston having the skirt portion thereof slotted generally longitudinally so as to permit expansion and contraction of said skirt; and having the skirt wall portions immediately marginal to said slot of generally the same over-all radial thickness as the principal radial thickness of the major portion of the skirt-wall and a spring operatively interposed between the juxtaposed edges of said slot and in generally pivotal relation to the juxtaposed sides of said slot, thereby to cause said skirt to expand by opposed tangential forces exerted by said spring;—portions of the spring interlocking with portions of the piston for preventing radial displacement of the former with respect to the latter, and interlocking means

for preventing the axial displacement of the spring with respect to the piston.

14. The combination of a trunk type piston having a skirt slotted generally longitudinally and having a transverse slot communicating with the inner end of said longitudinal slot (that is, nearest the head-end of the piston) and having the skirt wall portions immediately marginal to said slot of generally the same over-all radial thickness as the principal radial thickness of the major portion of the skirt-wall, and a spring member operatively interposed between the two juxtaposed edges of said longitudinal slot and in generally pivotal relation to the juxtaposed sides of said slot, and thereby to exert opposed tangential forces upon the two opposed sides of said skirt on either side of said slot;—portions of the spring interlocking with portions of the piston for preventing radial displacement of the former with respect to the latter, and interlock-

ing means for preventing the axial displacement of the spring with respect to the piston.

15. The combination of a piston having a skirt slotted generally longitudinally and having the skirt wall portions immediately marginal to said slot of generally the same over-all radial thickness as the principal radial thickness of the major portion of the skirt wall, a groove provided in each of the opposite side-walls of the slot in said skirt, and a spring member operatively interposed between the slot edges of said skirt within said grooves, and interlocking with said grooves so as to prevent displacement thereof with respect to the piston skirt in a radial direction, without restraining the independent radial expansion and contraction of the skirt portions on opposite sides of the slot;—said spring being generally pivotally related to the walls of said slot.

WILLIAM WUERFEL.
